CLAIM

The ornamental design for a whole blood treatment cartridge, as shown and described.

DESCRIPTION

FIG. 1 is a front, top, and side perspective view of a whole blood treatment cartridge;

FIG. 2 is a top plan view thereof; the bottom plan view, front

plan view, and back plan view being identical; and,

FIG. 3 is a side plan view thereof; the opposite side being a mirror image.

1 Claim, 2 Drawing Sheets
